SIGNALING SYSTEM

Filed Dec. 18, 1916

Inventor:
Burton W. Kendall.
by A. C. Kendall, Atty.

UNITED STATES PATENT OFFICE.

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK.

SIGNALING SYSTEM.

Application filed December 18, 1916. Serial No. 137,592.

To all whom it may concern:

Be it known that I, BURTON W. KENDALL, a citizen of the United States, residing at New York, in the county of New York and 5 State of New York, have invented certain new and useful Improvements in Signaling Systems, of which the following is a full, clear, concise, and exact description.

This invention relates to multiplex te- 10 lephony by means of modulated carrier currents, and more particularly to a system in which a plurality of modulated carrier waves and an audio-frequency wave are transmitted over a single high-frequency line. The features of the invention are, in 15 general, applicable also to radio transmission in which case the line would be replaced by an antenna. Each carrier wave is modulated by a signal which originates in a low- 20 frequency line, a plurality of which are associated with the high-frequency line.

The object of the invention is to secure 25 a two-way transmission of signals between the single high-frequency line and all of the low-frequency lines.

The invention provides for balancing the high-frequency line at all of the various carrier frequencies and at the audio-frequencies used, and each low-frequency line 30 is balanced at telephonic frequencies. Between the high-frequency line and the low-frequency lines are connected modulating and detecting circuits for changing the low-frequency messages into high-frequency 35 messages, and vice versa, and means for isolating and transmitting the audio-frequency message. The modulating circuits and the detecting circuits are connected in conjugate relation to the high-frequency line and its 40 balancing net work so that a modulated carrier wave will be sent out upon the high-frequency line without affecting the local detecting circuit. The transmitting circuits for the low-frequency message are 45 similarly placed in conjugate relation, as in the ordinary two-way repeating circuit.

The figure shows diagrammatically a system for carrying out the invention.

In the figure, the line 1 is adapted to send 50 and receive an audio-frequency message and also a plurality of modulated carrier waves. The low-frequency lines 2, 3 and 40 are each adapted to send and receive a low-frequency signal. Between the high-frequency line 1 and the low-frequency lines 2, 3 and

40 are connected suitable means which provide for the two-way transmission of signals. Connected in the high-frequency line 1 are the coils 4 and 5, across the mid-points of which is bridged the line 6, associated with the modulating circuits M_2 and M_3 , and the low-frequency repeating circuit R_1 . In the high-frequency line 1 is also connected the high-frequency net work or artificial line 7, which simulates the impedance of 60 the high-frequency line 1 at all of the carrier and audio-frequencies transmitted over the line 1. The high-frequency net work 7 may consist of a serially connected resistance and condenser, as shown in the patent 65 to Hoyt, No. 1,167,694, January 11, 1916, Artificial line. Inductively related with the coils 4 and 5, is the coil 8, connected in the line 9 with which are associated the detecting circuits D_2 , D_3 and the low-frequency 70 repeating circuit R_2 .

In the detecting circuit D_2 is the resistance 10 connected across the line 9. This resistance serves as a source of potential for one or more amplifiers A_2 of the audion 80 type. The grid 11 of this amplifier is maintained at a suitable negative potential by means of a battery 12. Space current is supplied in the output circuit of the amplifier A_2 through the impedance 13 by the 85 battery 14. The condenser 15 prevents current from the battery 14 from flowing through the filter F_2 , which selectively transmits the carrier frequency designed for the detecting circuit D_2 . The filter F_2 90 selectively transmits a modulated carrier wave of a given frequency to the detector d_2 which may be a thermionic detector as shown. The output circuit of the detector d_2 is coupled by means of the transformer 95 16 and coils 17, 18 and 19 to the low-frequency line 2. In the low-frequency line 2 are connected the coils 18 and 19 and the artificial line 20. Coils 17, 18 and 19 are inductively related, and bridged across the 100 mid-points of the coils 18 and 19 is the line 21 which transfers signals originating in the line 2 to the modulating circuit M_2 .

The modulating circuit M_2 comprises a modulator m_2 of the audion type, in the 105 input circuit of which is connected the secondary winding of transformer 22, the primary winding of which is connected in the line 21. The high-frequency generator 23, shunted by the resistance 24, is adapted to 110

supply high-frequency waves to the modulator m_2 . The space current in the output circuit of the modulator m_2 is supplied by the battery 25, through the impedance 26. This modulating scheme is described and claimed in United States patent to Van der Bijl No. 1,350,752, granted August 4, 1920, for high frequency signaling. The condenser 27 prevents current from battery 25 from flowing through the resistance 28, which serves as a source of potential for one or more amplifiers A_4 . The output circuit of the amplifier A_4 is tuned to the frequency supplied by generator 23 by means of the condenser 29. Modulated carrier waves are transferred from the output circuit of the amplifier A_4 to the loop resonant circuit C_2 , by means of the transformer 30. The loop resonant circuit C_2 is serially connected in the line 6, and is tuned to the frequency supplied by the generator 23.

The modulating circuit M_2 associated with the low-frequency line 3 is substantially the same as the modulating circuit M_2 just described, the differences being that the high-frequency generator 34 supplies a carrier wave of a frequency different from that supplied by the generator 23; also, the output circuit of the amplifier A_5 and the loop resonant circuit C_3 are tuned to the frequency supplied by the generator 34.

The low-frequency repeating circuit R_1 serves to transfer audio-frequency currents from the low-frequency line 40 to the line 6 associated with the high-frequency line 1. The line 40, similarly to the lines 2 and 3, is balanced at telephonic frequencies. By means of the amplifier A_6 in the repeating circuit R_1 , amplified audio-frequency currents are supplied through the filter F_1 and transformer 35 to the line 6. The filter F_1 cuts off all frequencies above telephonic frequencies, i. e., about 2500 cycles.

In shunt to that coil of transformer 35 connected in line 6 is the small condenser 36, which provides an easy path around this coil for the carrier waves from M_2 , M_3 , etc., without thereby short-circuiting the currents of audio frequencies supplied by this coil to line 6.

Each loop resonant circuit is highly selective for currents of the frequency for which it is tuned, while offering a path of low impedance to currents of different frequencies. The modulated carrier wave supplied by the circuit M_2 and the audio-frequency currents from circuit R_1 find a path of low impedance through the other loop resonant circuits C_2 , etc., connected in the line 6. If the loop-resonant circuits were not provided, the carrier wave supplied by circuit M_2 , for instance, would not be efficiently transmitted to the line 1, as this carrier wave would be impeded by the secondary winding of transformer 30, which transfers

the carrier wave from circuit M_2 to the line 6.

The modulated carrier waves supplied by the modulating circuits M_2 , M_3 , and the low-frequency wave from circuit R_1 , etc., are conducted by the line 6 to the mid-points of the coils 4 and 5. The current divides through the coils 4 and 5, one half going through artificial line 7, and the other half going out upon the high-frequency line 1. The currents flowing through coils 4 and 5 induce equal and opposing electromotive forces in the two halves of the coil 8, so that the messages are sent out upon the high-frequency line 1 in such a manner as not to thereby affect the detecting circuits D_2 , D_3 and the repeating circuit R_2 associated with the line 9. The lines 6 and 9 may be interchanged in their connection with the coils 4, 5 and 8, and a similar interchange may be made in the connections of the balancing networks associated with the low-frequency lines 2, 3, 40, etc. If desired, the modulating circuit M_2 and the corresponding detecting circuit D_2 may be designed to use the same carrier frequency.

The detecting circuits D_2 , D_3 are substantially the same, the only difference being the adjustment of the various elements whereby each detecting circuit handles the carrier frequency generated in its corresponding modulating circuit at a distant station, not shown. The amplifiers A_2 and A_3 are essentially unilaterally conducting, in order to prevent interaction of the filters F_2 and F_3 which are connected across line 9. Where filters are connected directly in parallel, there is a tendency for the terminal sections of one filter to act in part as a low impedance for currents of frequencies outside the transmission range of that particular filter. In certain cases this may seriously interfere with effective transmission to the other filters. Moreover, transients may be set up by one filter in consequence of electrical disturbances in the common line and these transients may then be applied to other filters to cause interfering disturbances to be transmitted thereby. The asymmetric property of the amplifiers prevents retransmission to the common line 9 of transients originating in any particular filter. Moreover, the high impedance of the input circuits of the amplifiers prevents the individual filter channels from in anywise serving as short circuits for each other across line 9.

An audio-frequency signal sent from a distant station over line 1 is transferred from line 9 by means of the repeating circuit R_2 to the low-frequency line 40. The resistance 37 and amplifier A_8 are similar to the corresponding elements in the circuits D_2 , D_3 . The filter F_3 suppresses all frequencies above telephonic frequencies and transmits the audio-frequency message to the line 40.

It will be apparent that audio-frequency currents originating in the line 2 will modulate the radio-frequency currents supplied by the generator 28 in the modulating circuit M_1 . This modulated carrier wave is sent out upon the high-frequency line 1 to a distant station not shown. The conjugate relation of lines 3 and 9 with line 1 and its balancing net work insures that this transmitted modulated wave will not affect the local detecting circuits D_2 , D_3 , and the repeating circuit R_2 . A modulated carrier wave or an audio-frequency wave transmitted from a distant station, not shown, will be received by the high-frequency line 1 and the corresponding low frequency signal current will be transferred to the proper low-frequency lines 2, 3, and 40 in consequence of the selective action of the filters associated with the local receiving circuits.

The audio-frequency currents supplied by the detector D_2 , for instance, will be transferred to the low-frequency line 2, the balancing net work associated with this line insuring that the low-frequency currents divide between the line 2 and the net-work 20, without being transferred by means of the line 21 to the modulating circuit M_2 .

It is obvious that in case the low-frequency repeating circuits such as R_1 , R_2 are not used, the line 1 may be an antenna, as wireless transmission may be used. Furthermore, any number of low-frequency lines may be associated with the high-frequency line in the same manner as lines 2 and 3.

What is claimed is:

1. A signaling system comprising a line for sending and receiving a plurality of signals, means for simulating the impedance of said line at all frequencies necessary for the transmission of said signals, a plurality of signal lines for sending and receiving simultaneous and non-interfering signals, and means common to all of said signal lines for simultaneously connecting said line and said signal lines for the two-way transmission of signals.

2. A signaling system comprising a high frequency line for sending and receiving a plurality of messages, means for simulating the impedance of said high frequency line at all frequencies necessary for the transmission of said messages, a plurality of low frequency lines for sending and receiving audio-frequency waves, and means between said high-frequency line and said low frequency lines common to said low frequency lines for the two-way transmission of signals.

3. A signaling system comprising a high frequency line for sending and receiving a plurality of modulated carrier waves having different carrier frequencies, means for simulating the impedance of said high frequency line at all of said carrier frequencies, a plurality of low-frequency lines for send-

ing and receiving audio frequency waves, and means between said high frequency line and said low frequency lines common to said low frequency lines for the two-way transmission of signals.

4. A signaling system comprising a high frequency line for sending and receiving a plurality of modulated carrier waves having different carrier frequencies, a balancing net work associated with said high frequency line and comprising means for simulating the impedance of said line at all of said carrier frequencies, a plurality of modulating circuits and corresponding detecting circuits associated in conjugate relation with said high frequency line and balancing net work, and a plurality of low frequency lines for sending and receiving audio-frequency waves, each of said modulating circuits and its corresponding detecting circuit being associated with one of said low frequency lines.

5. A signaling system comprising a high-frequency line for sending and receiving a plurality of modulated carrier waves having different carrier frequencies, a balancing net work associated with said high frequency line and comprising means for simulating the impedance of said line at all of said carrier frequencies, a plurality of modulating circuits and corresponding detecting circuits associated in conjugate relation with said high frequency line and balancing net work, a plurality of low frequency lines for sending and receiving audio frequency waves, a balancing net work associated with each of said low frequency lines and comprising an artificial line, each of said modulating circuits and its corresponding detecting circuit being associated in conjugate relation with one of said low frequency lines.

6. In combination, a high frequency signal line and balancing means for simulating its impedance at ordinary telephonic frequencies and through the frequency range of high frequency currents to be transmitted thereover connected thereto, means for transmitting currents within ordinary telephonic frequency range over said signal line, means for transmitting other currents of much higher frequencies over said line, a low frequency signal line and balancing means for simulating the impedance of said low frequency line connected thereto, and two-way repeater circuits between said lines connected at the points of connection of said lines with their respective balancing means.

7. A signaling system comprising a signaling line, a plurality of resistances shunted across said line, and an individual signaling circuit including an asymmetrically conducting device connected to two points of each resistance.

8. A signaling system comprising a line,

a plurality of resistances shunted across said line, and an individual signaling circuit connected to two points of each resistance, each of said signaling circuits including a thermionic repeater.

9. In combination a transmission line, a plurality of signaling circuits, each of said signaling circuits being connected to said line by a two way repeater circuit at least one of said repeater circuits comprising means for modulating a carrier current in accordance with signal currents impressed thereon by the corresponding signaling circuit and another of said repeater circuits comprising means for repeating currents of a single range of frequencies in both directions.

10. A transmission line and a plurality of signaling circuits, each of said signaling circuits being permanently connected to said line by a two-way repeater circuit, said repeater circuits having common points of connection to said line, and means for supplying speech frequency currents for transmission in both directions between said transmission line and one of said signaling circuits.

11. A repeating system comprising a high frequency line, a low frequency line, and means connecting said lines comprising two asymmetric channels transmitting in opposite directions, one of said channels including means for modifying carrier currents and the other of said channels including means for detecting carrier currents.

12. A high frequency line, an incoming channel and an outgoing channel conjugately connected thereto, a plurality of low frequency lines, and means including a modulator associated with the outgoing channel and a detector associated with the incoming channel for connecting each of said low frequency lines to said high frequency line.

13. A high frequency line, an incoming circuit and an outgoing circuit conjugately connected thereto, a plurality of signaling lines, means for connecting said signaling lines to said outgoing circuit, and means shunted across said incoming circuit for connecting said signaling line thereto.

14. A high frequency line and a plurality of low frequency lines connected thereto, at least one of said low frequency lines being connected to said high frequency line by a two-way repeater comprising a modulator and a detector, and another of said low frequency lines being connected to transmit low frequency currents directly to said high frequency line.

15. A line, means for simultaneously transmitting a plurality of different frequency speech modified carrier currents thereover, means for simultaneously transmitting ordinary speech frequency currents thereover, means for balancing said line for

currents of all the frequencies which it transmits, and conjugate transmitting and receiving circuits associated with said line and balancing means whereby the effect of currents in said transmitting circuit upon their respective local receiving circuits may be minimized.

16. A line, means for transmitting a plurality of different frequency carrier currents of higher than essential speech frequency thereover, means for transmitting speech frequency currents thereover, common means for balancing said line for currents of all the frequencies which it transmits, and conjugate transmitting and receiving circuits associated with said line and balancing means whereby the effect of currents in said transmitting circuits upon their respective local receiving circuits may be minimized.

17. A distributing system comprising a plurality of stations, and a periodic transmission line connecting each two adjacent stations for conveying high frequency currents, there being a current of a given high frequency assigned to each station, means at each station for simultaneously transforming low frequency currents to currents of the high frequencies assigned to that station, and a low frequency line for each station, each station comprising balancing means for the high frequency assigned to that station, and balancing means for the low frequency currents.

18. A common transmission line, a network connected to said line simulating its impedance at each of the frequencies of the waves transmitted thereover, a transmitting loop and a receiving loop conjugate with respect to said transmitting loop both connected to said line, means for supplying to said transmitting loop for transmission over said line a plurality of different frequency carrier waves each modified in accordance with an individual speech signal, and means for supplying audio frequency telephonic waves to said transmitting loop.

19. A common transmission line, a network connected to said line simulating its impedance at each of the frequencies of the waves transmitted thereover, a transmitting loop and a receiving loop conjugate with respect to said transmitting loop both connected to said line, means for selectively receiving from said receiving loop each of a plurality of different carrier frequency speech modified waves, and means for also selectively receiving from said receiving loop audio frequency telephonic waves representing speech signals.

20. A common transmission line, a plurality of signal lines, two-way repeating means between said transmission line and certain of said signal lines for repeating speech modified carrier currents as audio

- frequency speech currents and vice versa, and two-way repeating means between said transmission line and at least one of said signal lines for repeating audio frequency signal currents, all of said two-way repeating means having a common transmitting circuit and a common receiving circuit, said circuits being connected in conjugate relation to said transmission line.
- 19 21. A transmission circuit, means for supplying a plurality of different frequency currents thereto, individual selective means for selecting each of said different frequency currents from said circuit, and an individual asymmetrically conducting element connecting each of said selective means to said circuit, whereby said selective devices are prevented from interacting upon each other.
- 20 22. A transmission circuit, means for supplying a plurality of different frequency currents thereto, individual selective means for selecting each of said currents from said circuit, an individual repeater having an input circuit of high resistance connecting each of said selective means to said circuit, whereby said selective devices do not substantially affect the impedance characteristics of said line.
- 25 23. A multiplex system comprising a common transmission line, means for transmitting currents of different frequencies thereto, an individual circuit for each of said different frequency currents, separate selective means connecting each of said circuits to said line in energy transfer relation,
- 30 said selective means comprising filters effectively connected in parallel relation to each other with respect to said line and means interposed between each of said filters and said line to prevent transmission to said line of transients originating in the respective filters.
- 35 24. A multiplex system comprising a common transmission line, means for transmitting currents of different frequencies thereto, an individual circuit for each of said different frequency currents, separate selective means connecting each of said circuits to said line in energy transfer relation,
- 40 45 said selective means comprising filters connected effectively in parallel to each other with respect to said line, and a high impedance repeating element interposed between said line and each of said filters whereby any tendency of a filter to act as a short circuit for currents of frequencies outside its transmission range is eliminated.
- 45 25. A multiplex system comprising a common line, means for supplying thereto a plurality of different frequency carrier currents each modified in accordance with a lower frequency wave individual thereto, selective means for each of said carrier currents connected to said line, and an individual repeater of the audion type interposed between each of said selective means and the common line.
- 50 In witness whereof, I hereunto subscribe my name this 15th day of December A. D., 1916.
- 55 BURTON W. KENDALL.

Certificate of Correction.

It is hereby certified that in Letters Patent No. 1,445,141, granted February 13, 1923, upon the application of Burton W. Kendall, of New York, N. Y., for an improvement in "Signaling Systems," an error appears in the printed specification requiring correction as follows: Page 4, line 87, claim 17, for the words "and a periodic" read *an aperiodic*; and that the said Letters Patent should be read with this correction therein that the same may conform to the record of the case in the Patent Office.

Signed and sealed this 20th day of March, A. D., 1923.

[SEAL.]

KARL FENNING,
Acting Commissioner of Patents.
